BY *A. B. Bowman*
ATTORNEY.

UNITED STATES PATENT OFFICE.

JOHN DIERKS, OF KANSAS CITY, MISSOURI.

STOCK-FEEDER.

1,276,884.

Specification of Letters Patent. Patented Aug. 27, 1918.

Application filed February 1, 1918. Serial No. 214,868.

To all whom it may concern:

Be it known that I, JOHN DIERKS, a citizen of the United States, residing at Kansas City, in the county of Jackson and State of Missouri, have invented certain new and useful Improvements in Stock-Feeders, of which the following is a specification.

My invention relates to stock feeders for automatically feeding stock by the pressure 10 of the animal's nose against a portion of the feeding mechanism.

The objects of my invention are; First, to provide a device of this class which is simple and economical of construction, durable, 15 easily installed and does not readily get out of order; second, to provide a device of this class in which, when a certain quantity of food is in the trough it will automatically stop the feed.

With these and other objects in view as 20 will appear hereinafter, my invention consists of certain novel features of construction, combination and arrangement of parts as will be hereinafter described in detail and 25 particularly set forth in the appended claims, reference being had to the accompanying drawings and to the characters of reference thereon which form a part of this specification, in which:

Figure 1, is a sectional view of my feeder shown in connection with a fragmentary portion of a feed hopper, and Fig. 2, is a front elevational view thereof.

Similar characters of reference refer to 35 similar parts throughout the several views.

The bin 1, spiral 2, shaft 3, clutch piece 4, lever 5, link 6, clutch collar 7, feeding spider 8, ratchet wheel 9, ratchet pawl 10, shield 11 and brace 12 constitute the principle 40 parts of my stock feeder.

The bin 1 may be any shape desired and in the lower end is provided an aperture 1^a and a cylindrical piece 1^a adapted for the spiral 2 to revolve therein. From the inner 45 edge of this cylindrical piece 1^a is a slanting partition 1^b adapted to conduct the feed in said bin to the exposed end of this spiral 2. On the other side of the bin 1 is provided a slanting portion 1^c upon which is mounted a bearing 1^d adapted for a bearing for one end 50 of the shaft 3. The other end of said shaft is supported by means of the brace 12 which acts as a support for said shaft and is provided with a bearing 12^a for said shaft. 55 Mounted on this shaft, adapted to revolve in the cylindrical piece 1^a, is the spiral 2

which is adapted to conduct the feed from the bin 1 out through the cylindrical piece 1^a to the trough 1^c with the revolution of said spiral. Secured to the outward end of 60 the shaft just inside the bearing 12^a is a ratchet wheel 9 which engages with the ratchet pawl 10 which is pivotally mounted immediately above said shaft on the brace 12 so that it engages with the teeth in said 65 ratchet wheel so that when said ratchet wheel is turned in one direction, the ratchet pawl engages with its teeth and holds it in its turned position. Revolvably mounted on this shaft, adjacent this ratchet wheel, is the 70 spider 8 which is provided with a plurality of arms 8^a extending radially therefrom. This spider 8 is provided with a hub 8^b which is provided with a plurality of lugs 8^c which have faces perpendicular to the face 75 of said hub on one side and angled faces on the opposite side. Slidably mounted on the shaft 3 and provided with a key 4^a, is a clutch piece 4 which is provided with notches conforming to, and adapted to engage with 80 the lugs 8^c on the hub 8^b when said clutch piece 4 is in the proper relative position to said hub piece 8^b. This clutch piece 4 is provided with an annular groove 4^b adapted for the collar 7. To one side of the collar 7 is 85 pivotally connected the link 6 and to the other end of said link is pivotally connected the lever 5 which is pivotally mounted on the brace 5^a secured to the bin 1, adjacent the shaft 3. This lever 5 is adapted to hold 90 the clutch piece 4 normally in engagement with the hub 8^b thus providing a gravity actuated clutch, however, if a sufficient quantity of food is in the trough to press the extended end of the lever 5 upwardly and support the same the clutch piece 4 is moved 95 along said shaft away from the hub piece 8^b disengaging the clutch and allowing the spider 8 to be revolved without revolving the shaft 3 and spider 2 but when there is 100 not sufficient quantity of food in the trough, the spiral and shaft will revolve with the spider 8. This spider 8 is covered by means of the shield 11 so that only two or three of the arms are exposed so that the stock in feeding can only press on one or two of these arms at a time. Vertically mounted 105 on the shaft 3 on the crank 3^a is a rod 3^b which is adapted to agitate the food and keep it from packing and it is supported by 110 a bracket 3^c.

Though I have shown and described a

particular construction, combination and arrangement of parts, I do not wish to be limited to this particular construction, combination and arrangement but desire to include in the purview of my invention, the combination, construction and arrangement substantially as set forth in the appended claims.

It is obvious that with this construction, 10 there is provided a stock feeder in which the animal, by revolving the spider 8 when there is only a small quantity of food in the trough 1^a, will turn the spiral 2 causing the food in the bin to move outwardly through 15 the cylindrical piece 1^a to the trough; that when sufficient quantity of food is in the trough to press the extended end of the lever 5 upwardly, the clutch piece 4 will be disengaged from the hub piece 8^b and the 20 turning of the spider will then not affect the feeding mechanism; that the device is simple and economical of construction, durable, easily installed and does not readily get out of order.

Having thus described my invention, what I claim as new and desire to secure by Letters Patent, is:

1. In a stock feeder, the combination of a bin, provided with an aperture and a trough 30 extending therefrom, a cylindrical piece secured in the bottom of said bin, providing communication between said bin and said aperture, a spiral revolvably mounted therein, a spider mounted in front of said bin 35 over said trough and means for engaging and disengaging said spider with said spiral.

2. In a stock feeder, the combination of a bin provided with an aperture and a trough extending therefrom, a cylindrical piece secured 40 in the bottom of said bin providing communication between said bin and said aperture, a spiral revolvably mounted therein, a spider mounted in front of said bin over said trough, means for engaging and 45 disengaging said spider with said spiral and

means for preventing said spider from turning in one direction.

3. In a stock feeder, the combination of a bin provided with an aperture and a trough 50 extending therefrom, a cylindrical piece secured in the bottom of said bin, providing communication between said bin and said aperture, a spiral revolvably mounted therein, a spider mounted in front of said bin over said trough, means for engaging and 55 disengaging said spider with said spiral, means for preventing said spider from turning in one direction and means for covering a portion of said spider.

4. In a stock feeder, the combination of a 60 bin provided with an aperture and a trough extending therefrom, a spiral revolvably mounted in the bottom thereof, a feeding mechanism mounted in front of said bin over said trough adjacent the aperture in 65 said bin, gravity actuated means adapted to connect said feeding mechanism with said spiral and means in connection with said connection means whereby, when there is sufficient quantity of food in the trough, said 70 spiral and said mechanism will disconnect.

5. In a stock feeder, the combination of a bin provided with an aperture and a trough 75 extending therefrom, a spiral revolvably mounted in the bottom thereof, a feeding mechanism mounted in front of said bin over said trough adjacent the aperture in said bin, gravity actuated means adapted to connect said feeding mechanism with said spiral, means in connection with said 80 connecting means whereby, when there is sufficient quantity of food in the trough, said spiral and said mechanism will disconnect and means in connection with said spiral for agitating the food in said bin.

In testimony whereof, I have hereunto set my hand at Kansas City, Missouri, this 19th day of January, 1918.

JOHN DIERKS.
